UNITED STATES PATENT OFFICE

114,257

DESIGN FOR AN ADVERTISING CARD

Royal I. Blanchard, Worcester, Mass., assignor to Roy Toy Company, Worcester, Mass., a corporation of Massachusetts

Application October 3, 1938, Serial No. 80,227

Term of patent 3½ years

To all whom it may concern:

Be it known that I, Royal I. Blanchard, a citizen of the United States, residing at Worcester, in the county of Worcester and State of Massachusetts, have invented a new, original, and ornamental design for an Advertising Card, of which the following is a specification, reference being had to the accompanying drawing, forming part thereof.

Fig. 1 is a front view of an advertising card showing my new design, and
Fig. 2 is an edge view of the same.

I claim:

The ornamental design for an advertising card, as shown.

ROYAL I. BLANCHARD.
